MULTIPLE FILAMENT LAMP COMBINATION

Jasper Dulberg, Astoria, N. Y.

Application April 18, 1938, Serial No. 202,587

2 Claims. (Cl. 173—348)

The invention herein disclosed relates to multiple filament lamps, particularly those of the type covered in Dulberg Patent 2,082,326 and patent application Ser. 189,956.

- 5 Objects of the invention are to provide a practical and inexpensive multiple filament lamp structure adapted for use in any ordinary lamp socket and more particularly to arrange the base and filament switch mechanism for the lamp in 10 the form of a unit adapted for mounting in an ordinary lamp socket and which is separable from the lamp itself, thus being in the nature of an "adapter" engageable in the lamp socket and adapted to receive a multi-filament globe.
- 15 Further objects and the novel features of construction, combinations and relations of parts by which all objects are attained are hereinafter set forth or will appear in the course of the following specification.
- 20 The drawings accompanying and forming part of the specification illustrate a practical commercial embodiment of the invention.

The structure however may be modified and changed in various ways all within the true intent and broad scope of the invention as hereinafter defined and broadly claimed.

Fig. 1 is a broken part sectional view of the complete lamp combination.

Fig. 2 is a view of the socket end of the adapter as separated from the lamp globe.

Fig. 3 is a broken sectional detail substantially on the line 3—3 of Fig. 2.

Fig. 4 is a broken cross-sectional view on substantially the plane of line 4—4 of Fig. 1, omitting the screw shell terminal.

Fig. 5 is a cross-sectional view as on substantially the line 5—5 of Fig. 1.

Fig. 6 is a diagrammatic view of the parts in the position indicated in Fig. 1 and showing how in such position the filament 13 will be illuminated.

Fig. 7 is a similar view showing how with the socket portion turned one step to the right, the filament 12 will be illuminated.

Fig. 8 is a diagrammatic view illustrating the switch mechanism turned to the third position to accomplish illumination of both filaments.

The present invention, as in the prior Dulberg patents, comprises the equivalent of a two part lamp base, one part designated 10, carrying the lamp globe 11, with the series connected filaments 12, 13, and having screw ring 14, engaging screw socket 15, in said base part 10. This globe further is shown as having center contact 16, and end ring contact 17. The filaments are indicated as connected together and as connected by a common supporting connection 18, to screw terminal 14, and with the outer end of filament 13, connected by support 19, with center contact

16, and the outer end of filament 12, connected by support 20, with the ring terminal 17.

The first lamp base part 10, is shown as having a reduced end portion 21, opposite the socketed end which receives the screw base of the bulb and as mounting the second base part carrying the screw shell contact terminal 22, and center lamp contact 23. This center contact is shown as a contact head on the outer end of the stud 24, fixed in the first base part. A spring 10 25, between this contact head and the insulating disc 26, closing the end of the screw shell contact 22, provides constant electrical connection between said contact head and the center contact bushing 27, seated in said insulating disc. 15 This center bushing is shown extended and inclined in Figs. 1 and 5, to constitute an elongated contact. Similar elongated inclined contacts 28, 29, are shown set in the face of the insulating button 26, secured as by eyelets 30, in electrical 20 connection with the surrounding screw shell contact 22.

Loosely mounted on the stud 24, between the two relatively rotatable base members 10 and 26, is shown an insulating disc 31, carrying 25 spaced inclined contact arms 32, 33, 34, for engagement with inclined contacts 27, 28, 29. These intermediate contacts are shown as secured on the insulating carrier 31, by studs 35, 36, 37, surrounded by springs 38, and projecting into tubular eyelets 39, 40, 41, in the first base member 10. The tubular rivets or eyelets 39, 40, 41, project up into the socketed end of the base part and secure in place the spring contact 42, for engaging center contact 16, of the bulb, the spring contact 43, for engaging the end contact ring 17, and the angled lug 44, at the base of the shell contact 15, respectively.

The lamp base attachment or adapter body is shown as having an extended end flange 45, lined 40 or roughened at 46, to provide a firm grip for the fingers.

The two relatively rotatable parts of the base structure are coupled in non-rotative relation in the illustration by having the screw shell part 45 22, notched at 47, Fig. 1, to receive lugs 48, on the other part. This coupling however, may be disengaged by pulling the first base part outwardly in respect to the second part against the tension of spring 25, sufficiently to release the lugs 48, 50 from notches 47.

The adapter can be used in any ordinary lamp socket and, combined as indicated with a double filament lamp, be employed to select either one or the other, or both filaments in parallel, thus 55 to give three degrees of illumination. With the three contact form of lamp screwed in the socket of the adapter as in Fig. 1, the inner ends of the two filaments will be connected at 18, with the socket shell 15, of the adapter and the outer ends 60

be connected with contacts 42, and 43. From these, current is conducted to the spring contacts or brushes 34, 32 and 33, on the front floating contact carrier 31. In the relation shown in Figs. 1 and 6, with brush 34, in engagement with contact 28, and brush 32, in engagement with contact 27, and brush 33 in engagement with contact 29, only the filament 13 will be illuminated, the circuit then being from center contact 23, 24, through spring 25 and contact 27, brush 32, spring 38 and tubular eyelet 39, spring 42, center contact 16, conductor 19, filament 13 and conductor 18 to screw shell 14, screw socket 15, eyelet 41, brush 34 and contact 28 to the screw shell terminal 22. In this position, the filament 12 while actually in circuit, through the return path 20, 43, 40, 33, 29, does not become illuminated because the resistance of such filament is such as to cause the current to return through low resistance return path 18, etc., for filament 13. With partial relative rotation of the lamp base parts to the position shown in Fig. 7, to carry brush 32, off contact 27 and snap it into engagement with contact 28, filament 13 will cease to be illuminated and in the same movement, filament 12 will be cut in full circuit by brush 33, which through eyelet 40 and spring 43, Fig. 3, connects with the terminal ring 17. From this point the flow is through support 20, filament 12 and low resistance return through support 18, screw shell terminals 14, 15, eyelet 41, brush 34, and contact 29, connected with screw shell terminal 22.

With the next step of relative rotation Fig. 8, the brush 34, which through the eyelet 41, is connected with the screw shell 15 and hence with the screw contact 14, of the lamp globe, by engagement with contact 27, establishes current flow through the center connection 18 to the two filaments 12, 13. At such time, the other two brushes 32 and 33, will be in engagement respectively with contacts 29 and 28, connected with the screw shell terminal 22, so both filaments 13 and 12, will then have low resistance return connections to the screw shell terminal 22.

The two relatively rotatable parts of the adapter are normally coupled at 47, 48, so that the adapter may be readily screwed into or out of a current supply socket. The spring 25, Fig. 1, which normally holds these parts interlockingly engaged, is readily yieldable to permit the upper or socket portion of the adapter to be pulled out far enough to release lugs 48, from notches 47, whereupon the upper socket portion 55 may be turned one or more steps and dropped back into interlocked engagement again. These same adjustments can be effected with or without the lamp in place in the adapter. The adapter therefore may be considered and used either as an attached part of the lamp or as a wholly separate unit to be inserted in a lamp socket or to be applied to a lamp globe, whenever required. The detachability of the supporting base and switch mechanism is particularly desirable as affording a structure separate from the filament carrying portion and which may be used with new lamps indefinitely as filaments burn out or lose efficiency. In addition to its particular utility in connection with or part of multifilament lamps, the adapter may be used also with single filament lamps. Thus if a multiple filament lamp should burn out and no other such lamp be immediately available, lighting service may be maintained by

simply screwing an ordinary single filament lamp in the socket of the adapter. The two relatively rotatable parts of the adapter constitute a two part lamp base extension with the lower, outer, exposed plug portion carrying the screw shell and center lamp terminal elements and the upper portion carrying the three contact terminals for the double filament lamp inserted or to be inserted therein.

What is claimed is:

1. An adapter, comprising plug and socket portions connected in coaxial relatively rotatable relation, screw shell and center plug contacts on said plug portion, screw shell and center socket contacts on said socket portion, relatively rotatable and axially yieldable switch contacts between said relatively rotatable plug and socket portions and yieldingly connected with both said plug portion and said socket portion contacts, there being three switch contacts carried by said plug portion and three coating similarly positioned switch contacts carried by said socket portion, said switch contacts being always in engagement but in different relations in the three possible relatively rotated positions of the plug and socket portions, two of the switch contacts carried by the plug portion being connected with one of the contacts of that portion and the other of such switch contacts being connected with the other contact of said plug portion, the socket portion having a lamp contact in addition to said screw shell and center contacts and the three switch contacts carried by said socket portion being connected with said three contacts on said socket portion, and an exposed switch operating ring of insulating material projecting from said socket portion and forming a handle for rotating said socket portion in respect to said plug portion for effecting operation of said switch contacts.

2. An adapter, comprising plug and socket portions connected in coaxial relatively rotatable relation, screw shell and center plug contacts on said plug portion, screw shell and center socket contacts on said socket portion, relatively rotatable switch contacts between said relatively rotatable plug and socket portions and connected with said plug portion and said socket portion contacts, there being three switch contacts carried by said plug portion and three coating similarly positioned switch contacts carried by said socket portion, said switch contacts being always in engagement but in different relations in the three possible relatively rotated positions of the plug and socket portions, two of the switch contacts carried by the plug portion being connected with one of the contacts of that portion and the other of such switch contacts being connected with the other contact of said plug portion, the socket portion having a lamp contact in addition to said screw shell and center contacts and the three switch contacts carried by said socket portion being connected with said three contacts on said socket portion, and an exposed switch operating ring of insulating material projecting from said socket portion and forming a handle for rotating said socket portion in respect to said plug portion for effecting operation of said switch contacts.

JASPER DULBERG.
